UNITED STATES PATENT OFFICE

JOSEPH C. YECKER, OF LANCASTER, PENNSYLVANIA

GLIDER PLANE

Application filed May 29, 1930. Serial No. 457,138.

This invention relates to new and useful improvements in a glider.

The invention has for an object the provision of a device of the class mentioned which is of simple durable construction, dependable in use and efficient in action, and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:—

Fig. 1 is a plan view of a glider constructed according to this invention.

Fig. 2 is a side elevational view of Fig. 1.

Fig. 3 is an end elevational view of Fig. 1 looking from the right hand end.

Fig. 4 is an enlarged fragmentary transverse sectional view taken on the line 4—4 of Fig. 2.

Fig. 5 is a fragmentary enlarged sectional view taken on the line 5—5 of Fig. 1.

Fig. 6 is an enlarged fragmentary sectional view taken on the line 6—6 of Fig. 2.

Fig. 7 is an enlarged fragmentary sectional view taken on the line 7—7 of Fig. 1.

Fig. 8 is a fragmentary elevational view looking in the direction of the line 8—8 of Fig. 3.

Fig. 9 is a view similar to Fig. 5, but illustrating a modified form.

Fig. 10 is a view similar to a side view of Fig. 6, but illustrating another modification for holding the rods in adjusted positions.

Fig. 11 is a fragmentary view similar to a portion of Fig. 2, but illustrating another embodiment of the invention.

The glider consists of transverse main wings 12 consisting of a frame including crossed flexible rods 13 and covering material 14 forming wings simulating a bow tie, a longitudinal glider body 15 above said main wings 12 and having its nose 16 located to the front of the point of crossing 17 of said rods 13 and including a longitudinal rod 18,

and a resilient frame 19 connected with the outer ends 20 of said main wings 12 and holding said body 15 spaced from said main wings 12, shaper rods 21 attached at their front ends 22 on the nose 16 and intermediate 55 of their ends as at 23 on said crossed rods 13 near the point of crossing 17, and means for adjustably connecting the rear ends 24 of said shaper rods 21 with said longitudinal rod 18 for adjusting the bowed condition of 60 said main wings 12.

The frame used for forming the main wings 12 and including the said flexible crossed rods 13 also includes longitudinal end strips 25. The covering material 14 is bent over these end strips 25, as clearly shown in Fig. 7, and stitches 26 serve to hold these ends engaged in place. The inner ends of the covering material 14, indicated by reference numerals 27 in Fig. 8, 70 terminate a short distance from the point of crossing 17 of the rods 13. A wire 28 engages over the rods 13 at the point of crossing 17 and accomplishes the holding of the rods in position.

The glider body 15 consists of a frame 29 formed of wire, which includes curved side forming wires as may be seen from an inspection of Fig. 1. At the front end these side forming wires are bent down constituting the nose 16 of the glider body. A tail 30 is supported upon the rear ends of the side forming wires of frame 29. As clearly shown in Fig. 1, these side forming wires cross at a point to the front of the tail. This point 75 is indicated by reference numeral 31. The glider body 15 is concluded with a cloth element 32 engaged upon the said frame 29. The edges of this cloth are turned around the wires forming the frame 29, as may be seen from an inspection of Fig. 5, and stitches 33 serve to hold these ends in place. The tail 30 consists of a wire frame 34 preferably of rectangular shape and cloth 35 engaged upon the frame.

The resilient frame 19 consists of a pair of crossed wire rods 36. These rods are positioned substantially directly above the crossed rods 13 and have their point of crossing directly above the point 17. The manner of at- 100

taching the frame 19 to the glider body 15 consists of a piece of wire 37 engaged over the longitudinal rod 18 and over the point of crossing of the wires 36 as clearly shown in Figure 4, and the ends of the wire 37 are 5 twisted for maintaining the position of the parts. The ends of the wires 36 are bent downwards so as to accomplish the spacing of the wings 12 from the body 15. The free ends of the wires 36 are attached to the ends 10 20 of the wings as before recited.

As shown on the drawing, there are two shaper rods 21 located so as to straddle the rod 18. At the front ends of the shaper rods 21, a wire 38 is engaged upon these parts and the longitudinal rod 18 for accomplishing the attaching of the shaper rods upon the nose 16 of the body 15. The shaper rods 21 as before recited are attached intermediate of their ends on the crossed rods 18 near the point of crossing 17, as clearly shown in Fig. 8. The rods 21 are slightly bent at the point where they cross the rods 13 and wire 39 is engaged over all of the rods 13, 21 for holding these parts together. 25

The means for adjustably connecting the rear ends 24 of the shaper rods 21 with said longitudinal rod 18 for adjusting the bowed condition of the main wings, comprises a wire 40 wound transversely around and between the rod 18 and the rods 21. The ends 41 of this wire are twisted so as to tightly hold all of the wires in relative positions. For adjusting the bowed condition of the main wings 12 it is merely necessary to slightly loosen the twisted ends 41 of the wires and then to move the ends 24 to different positions along the rod 18. Such new position is indicated by the dot and dash lines 42 in Fig. 2. These dot and dash lines also indicate a new bowed condition of the main wings 12. A gas bag or balloon may be engaged beneath the glider body 15 and above the main wings 12 so as to add buoyancy to the glider. 40

In Fig. 9 a modified means has been shown 45 for attaching the cloth 32 upon frame 29. This means is shown to consist of snap fasteners 43 arranged to hold the edges of the cloth 32 to adjacent portions of the cloth so as to maintain position upon the frame 29.

In Fig. 10 a modified means has been shown 50 for adjustably connecting the rear ends 24 of the shaper rods 21 with said longitudinal rod 18 for adjusting the bowed condition of the main wings 12. This means is shown to consist of a bracket 44 slidably mounted upon the rod 18 and rigidly attached upon the ends 24. A catch 45 is mounted upon the rod 18 and is adapted for holding the bracket 44 in one 55 adjusted position. A tension spring 46 is attached upon the bracket 44 at one of its ends and at its other end upon a collar 47 fixed upon the rod 18 so as to normally urge the bracket 44 to a different position than that 60 restricted by the catch.

The catch 45 consists of a headed pin 48 70 slidably engaged thru the rod 18 and having its free end turned inwards so as to engage in an aperture formed in the bracket 44. A spring 49 acts between the head of the pin 48 and the rod 18 for urging the catch into its operative position. A set screw 50 is threadedly engaged thru the collar 47 and is adapted to restrain the sliding movement of the bracket 44 as urged by the spring 46. For this reason a stop lug 51 projects from the bracket 44 and is abuttable against the end of the set screw 50. A lock nut 52 engages on the set screw 50 and is abuttable against the collar 47 for locking the set screw in any desired adjusted positions. 75

The rudder 30', propeller 15' and motor 15^a may be of any of the conventional type.

In the modified form of the device illustrated in Fig. 11, a paddle propeller 53 has also been provided so that the glider may be 80 propelled thru the air while gliding. As shown on the drawing, the paddle propeller 53 is mounted upon the body 15. It consists of a rotatable casing 54 connected with a driver gear 55 carrying a chain 56 extending over a pinion 57 rotatively supported upon a bracket 58. Foot pedals 59 are connected with the pinion 57 so that upon rotation the casing 53 is turned. For the comfort of one 85 using the glider a seat 60 is mounted upon the body 15 to the rear of the bracket 58. Guard rods 61 partially encircle the seat 60 for protecting one sitting on the seat against falling out. The paddle propeller 53 also includes 90 an idler cam 62 within the casing 54 and a plurality of blades 63 extending thru slots in the casing and pivotally connected with the idler cam. Upon rotation of the casing 54 95 the blades 63 are caused to rotate and simultaneously move in and out from the casing. 100

While I have shown and described the preferred embodiment of my invention, it is to be understood that I do not limit myself to the precise construction herein disclosed and the right is reserved to all changes and modifications coming within the scope of the invention as defined in the appended claims. 110

Having thus described my invention, what I claim as new, and desire to secure by United States Letters Patent is:— 115

1. A glider, comprising transverse main wings consisting of a frame including crossed flexible rods and covering material forming wings simulating a bow tie, a longitudinal glider body above said main wings and having its nose located to the front of the point of crossing of said rods and including a longitudinal rod, a resilient frame connected with the outer ends of said main wings and holding said body spaced from said main wings, shaper rods attached at their front ends on said nose and intermediate of their ends on said crossed rods near the point of crossing, and means for adjustably connect- 120

ing the rear ends of said shaper rods with said longitudinal rod for adjusting the bowed condition of said main wings.

2. A glider, comprising transverse main wings consisting of a frame including crossed flexible rods and covering material forming wings simulating a bow tie, a longitudinal glider body above said main wings and having its nose located to the front of the point of crossing of said rods and including a longitudinal rod, a resilient frame connected with the outer ends of said main wings and holding said body spaced from said main wings, shaper rods attached at their front ends on said nose and intermediate of their ends on said crossed rods near the point of crossing, and means for adjustably connecting the rear ends of said shaper rods with said longitudinal rod for adjusting the bowed condition of said main wings, said main wings also include longitudinal end strips for holding down the ends of said covering material.

3. A glider, comprising transverse main wings consisting of a frame including crossed flexible rods and covering material forming wings simulating a bow tie, a longitudinal glider body above said main wings and having its nose located to the front of the point of crossing of said rods and including a longitudinal rod, a resilient frame connected with the outer ends of said main wings and holding said body spaced from said main wings, shaper rods attached at their front ends on said nose and intermediate of their ends on said crossed rods near the point of crossing, and means for adjustably connecting the rear ends of said shaper rods with said longitudinal rod for adjusting the bowed condition of said main wings, said glider body comprising a wire frame including curved side forming wires, and cloth material covering said frame.

4. A glider, comprising transverse main wings consisting of a frame including cross flexible rods and covering material forming wings simulating a bow tie, a longitudinal glider body above said main wings and having its nose located to the front of the point of crossing of said rods and including a longitudinal rod, a resilient frame connected with the outer ends of said main wings and holding said body spaced from said main wings, shaper rods attached at their front ends on said nose and intermediate of their ends on said crossed rods near the point of crossing, and means for adjustably connecting the rear ends of said shaper rods with said longitudinal rod for adjusting the bowed condition of said main wings, said longitudinal glider body includes a tail attached on its rear.

5. A glider, comprising transverse main wings consisting of a frame including crossed flexible rods and covering material forming wings simulating a bow tie, a lon-

gitudinal glider body above said main wings and having its nose located to the front of the point of crossing of said rods and including a longitudinal rod, a resilient frame connected with the outer ends of said main wings and holding said body spaced from said main wings, shaper rods attached at their front ends on said nose and intermediate of their ends on said crossed rods near the point of crossing, and means for adjustably connecting the rear ends of said shaper rods with said longitudinal rods for adjusting the bowed condition of said main wings, said resilient frame comprises crossed rods substantially superimposed upon the crossed rods forming said main wings, a crossed point of said latter rods being attached upon said glider body and the free ends upon said main wings.

6. A glider, comprising transverse main wings consisting of a frame including crossed flexible rods and covering material forming wings simulating a bow tie, a longitudinal glider body above said main wings and having its nose located to the front of the point of crossing of said rods and including a longitudinal rod, a resilient frame connected with the outer ends of said main wings and holding said body spaced from said main wings, shaper rods attached at their front ends on said nose and intermediate of their ends on said crossed rods near the point of crossing, and means for adjustably connecting the rear ends of said shaper rods with said longitudinal rod for adjusting the bowed condition of said main wings, comprising a wire wound transversely around and between said longitudinal rods and said shaper rods and having its ends twisted together.

7. A glider, comprising transverse main wings consisting of a frame including crossed flexible rods and covering material forming wings simulating a bow tie, a longitudinal glider body above said main wings and having its nose located to the front of the point of crossing of said rods and including a longitudinal rod, a resilient frame connected with the outer ends of said main wings and holding said body spaced from said main wings, shaper rods attached at their front ends on said nose and intermediate of their ends on said crossed rods near the point of crossing, and means for adjustably connecting the rear ends of said shaper rods with said longitudinal rod for adjusting the bowed condition of said main wings, comprising a bracket slidably mounted upon said longitudinal rod and rigidly connected to the rear ends of said shaper rod, a catch for holding the bracket in a fixed position on said longitudinal rod, means for resiliently urging said bracket away from said fixed position so as to accomplish the bowing of said main wings, and an adjustable stop for limiting new po-

sitions of said bracket for limiting the amount of bowing of said wings.

8. A glider, comprising transverse main wings consisting of a frame including crossed flexible rods and covering material forming wings simulating a bow tie, a longitudinal glider body above said main wings and having its nose located to the front of the point of crossing of said rods and including a longitudinal rod, a resilient frame connected with the outer ends of said main wings and holding said body spaced from said main wings, shaper rods attached at their front ends on said nose and intermediate of their ends on said crossed rods near the point of crossing, means for adjustably connecting the rear ends of said shaper rods with said longitudinal rod for adjusting the bowed condition of said main wings, and means for propelling said glider with paddles for adding to the gliding effect.

In testimony whereof I have affixed my signature.

JOSEPH C. YECKER.
